FIG. of. 1.

FIG. of. 2.

FIG. of. 3.

FIG. of. 4.

FIG. of. 5.

INVENTOR,
August Franz,
J. M. Woodward,
ATTORNEY.

UNITED STATES PATENT OFFICE.

AUGUST FRANZ, OF GARFIELD, NEW JERSEY.

DEVICE FOR CLEARING OBSTRUCTIONS FROM RAILWAY TRACKS.

Application filed September 13, 1921. Serial No. 500,406.

To all whom it may concern:

Be it known that I, AUGUST FRANZ, a citizen of Poland, residing at Garfield, in the county of Bergen and State of New Jersey, have invented certain new and useful Improvements in Devices for Clearing Obstructions from Railway Tracks, of which the following is a specification.

The object of this invention is to provide means for removing from railway tracks obstacles, such as nuts, bolts and the like, that are too small to be removed by the usual cow-catcher or other fixed fender but yet might cause derailing of the rolling stock, the same to be constructed so as to operate with uniform certainty regardless of how small such obstacles may be and yet to pass freely irregularities in the track, as at the joints between the rails.

20 In the drawing,

Figure 1 is a side elevation of a railway vehicle truck having the means constituting this invention attached thereto;

25 Figure 2 is a front elevation of what is shown in Fig. 1, but on a larger scale;

Figure 3 is a plan, only a fragment of the truck appearing;

Figure 4 is a side elevation of the device and one of the rails; and

30 Figure 5 illustrates a detail.

To the under side of the frame *a* of the railway truck seen in Figs. 1, 2 and 3 are attached, a suitable distance apart, forwardly projecting brackets or hangers *b*. They are preferably secured to the truck by bolts *c*, one or more washers *d* being interposed between them and the truck frame if required so as to bring the fender devices hereinafter referred to the proper distance 40 above the rails to act most effectively.

These brackets are connected at their forward ends by the transverse shaft *e* which may be kept against endwise movement by the set screws *f* tapped into the brackets.

45 Each end of this shaft overhangs one of the rails *g* of the railway.

On each end of the shaft is fulcrumed the aforesaid fender device *h*, the same being kept against lateral shifting by the collars *j* and nuts *i*. Each fender device is a lever whose lower arm or fending portion *h'* is curved rearwardly and has its lower end arranged obliquely to the track (Fig. 3), its point or extremity being preferably not forward of the vertical plane of the axis of movement, of the device, whereby such point

can be arranged very close to the top of the corresponding rail *g* and yet not have its movement opposed by the rail when the device moves backward on its fulcrum. The other arm *h''* extends upwardly from the fulcrum portion of the lever.

On each bracket or hanger *b* is suitably fixed an arm *k* which projects laterally back of the upper arm of the corresponding fender device, which in normal position bears against said arm *k* which forms a stop therefor.

The fender devices are held normally bearing against their stops *k* by the following means: The upper arm of each such device has a hole *n* formed therein, the same being preferably enlarged, as at *n'*, at the outer side of the arm. These holes are penetrated by the rod *o* which has a knob *o'* to

seat in the enlargement *n'* of one hole and a spherical nut *o''* to seat in the enlargement of the other hole, the nut being screwed onto the rod. The rod thus couples together

70 the upper arms of the two levers, but in such a manner that either lever can move on its fulcrum independently of the other, the joint between each lever and the bar being a universal one. The rod is connected with some fixed part on or of the truck 75 frame, as the brackets or hangers *b*, by spring means *p*.

In operation the two fender devices stand as in Fig. 1, being held upright against the stops *k* by the means *o*, *p*. They are ad- 90 justed to such an elevation that their lower ends will be very close to the rails—suffi-

ciently close that they will engage and remove from the rails such obstacles as, nuts, bolts and the like that are small but yet 95 might cause derainment of the vehicle on its encountering them. If either fender device

should engage the end of a rail possibly set a little higher than the neighboring rail, as at *A* in Fig. 4, it will yield backwardly until such obstruction has been passed, and this, moreover, without moving the other fender device out of position to remove an 100 obstacle that might happen to be present on the other rail.

The arm *h'* of each fender device is made of sufficient breadth so as to extend across the full width of the corresponding rail regardless of any lateral lost motion of the truck on the rails and of the curvature of 110 the rails.

Having thus fully described my invention,

what I claim as new and desire to secure by Letters Patent is:—

In combination, with a railway vehicle of the class having a pair of wheels to respectively run on two tracks, a pair of fender devices each pivoted to move on a horizontal axis extending transversely and forward of the wheels and respectively arranged in front of the wheel and each having a depending fending portion, means to support said de-

vices on the vehicle having stops limiting the forward movement of said devices, a bar connecting said devices and having a universal joint connection with each of them, and spring means connected with the bar and holding said devices against the stops.

In testimony whereof I affix my signature.

AUGUST FRANZ.
